US0D1069699S

(12) **United States Design Patent** (10) **Patent No.:** **US D1,069,699 S**
Lee et al. (45) **Date of Patent:** **** Apr. 8, 2025**

(54) **SMART WATCH WIRELESS CHARGING CRADLE**

(71) Applicant: **SINJIMORU CO., LTD**, Seoul (KR)

(72) Inventors: **Bum Pil Lee**, Seoul (KR); **Joon Ho Sung**, Yongin-si (KR)

(73) Assignee: **SINJIMORU CO., LTD**, Seoul (KR)

(**) Term: **15 Years**

(21) Appl. No.: **29/888,246**

(22) Filed: **Mar. 29, 2023**

(30) **Foreign Application Priority Data**

Sep. 30, 2022 (KR) 30-2022-0040329

(57) **CLAIM**

The ornamental design for a smart watch wireless charging cradle, as shown and described.

DESCRIPTION

FIG. 1 is a perspective view of smart watch wireless charging cradle, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines depict portions of the smart watch wireless charging cradle that form no part of the claimed design.

1 Claim, 6 Drawing Sheets
